HOLGER NIELSEN, OF COPENHAGEN, DENMARK.

REFRIGERATING MACHINE.

Application filed March 25, 1924. Serial No. 701,842.

To all whom it may concern:

Be it known that I, HOLGER NIELSEN, subject of the King of Denmark, residing at Copenhagen, Denmark, have invented 5 certain new and useful Improvements in Refrigerating Machines, of which the following is a specification.

Refrigerating machines are known consisting of a compressor enclosed in a small 10 rotary tank which communicates with another vessel containing the medium, for instance sulphurous acid, which is compressed by being directed to the compressor, and is then cooled, until it assumes liquid state, 15 whereafter it is returned to the tank, where the liquid will expand and, thereby, return into gaseous state, during which process it will acquire a very considerable quantity of heat.

20 In the known apparatus, the rotary tank enclosing the compressor is generally of spherical shape, and is fitted with a central tubular shaft, onto which the two obliquely disposed compressor cylinders are hung together with a heavy weight serving to prevent the compressor cylinders from following the rotation of the outer cylinder.

In the tank space is provided for the 25 liquid sulphurous acid and for the oil required for lubrication of the cylinders.

These known apparatuses, however, are subject to several drawbacks, which materially impede their use. In this connection, it may be noted that it has been difficult to 30 make the weight sufficiently heavy to prevent it from following the rotation of the vessel, and it has been difficult to prevent the oil from becoming mixed with the condensed sulphurous acid and, finally, the 35 start has been difficult owing to the large difference of pressure between the two sides of the compressor.

The present invention has now for its object to remedy these drawbacks, and this 40 result is attained principally by replacing the two compressor cylinders disposed obliquely below the shaft by two cylinders placed in line and in the horizontal diametrical plane of the vessel. As a result 45 space is acquired for a considerably heavier weight, whereby the latter is secured against following the rotation of the vessel. There are also provided, within the tank, 50 two annular partitions separating the lubricating oil and the liquid sulphurous acid 55 into an intermediate layer of sulphurous

acid extracted by centrifugal force and two outer layers of oil, a scraping pipe being provided for returning the liquid sulphurous acid to a collecting vessel, while scraping pipes return the oil from the two oil layers to an oil vessel disposed above the compressor cylinders.

Finally there is provided on the tubular shaft a valve the spindle of which, while actuated by the centrifugal force generated by the rotation, will stop the connection between the pipe and the tank, while the spindle, when the rotary speeds drops below a certain limit, will open this connection and, thereby, equalize the pressure difference.

One construction of the invention is shown on the drawing.

Fig. 1 showing the entire device in side 75 elevation with the compressor tank in section.

Fig. 2 on a larger scale a horizontal section of the compressor tank and the compressor cylinder,

Fig. 3 on a still larger scale a section of the pressure equalizing valve.

The device consists thus principally of the known elements, viz., an evaporator 1 in which the condensed sulphurous acid, admitted by way of the narrow central pipe 2 from a small vessel 3 in the compressor tank 4, expands and again becomes gaseous, whereafter it is returned to the compressor cylinders 6, 7 by way of a pipe 5 co-axial 80 with pipe 2. Finally there is provided a heavy weight 8.

By the invention here referred to it is novel to have the two cylinders 6 and 7 disposed in the horizontal diametrical plane of 85 the tank 4, while there is employed only one single block piston 10, which is given a reciprocating motion from an eccentric 90 100 provided on the tubular shaft 5, the said eccentric being adapted to move in an annular bearing medially of the piston 10. In consequence of the cylinders 6 and 7 being located at such high level there will be room for a much larger and, therefore, heavier weight.

105 No piston rings or the like are used for securing tightness between the piston 10 and the inner surfaces of the cylinders 6 and 7, and a rather powerful lubrication must therefore be used. In order, however, 110 to prevent liquid sulphurous acid from being introduced into the compressor cylinder

ders together with the oil means are provided according to the present invention, for effecting a separation between the oil and the liquid sulphurous acid by centrifugal action.

For this purpose there are provided in the tank 4 two partition rings 13 and 14 having perforations 15 and arranged close to the wall of the tank 4. As a result, during the speedy rotation of the tank a separation between the oil and the condensed sulphurous acid will be effected, the heavier sulphurous acid forming a circular band 16 between the two separating rings 13 and 14 as shown on the drawing, there being still left some sulphurous acid outside of the rings, but next to the wall of the tank, while the lighter oil will form two bands 17 and 18 outside of the partition rings 13 and 14. There is then, as mentioned before, provided a scraping pipe 19 leading from the sulphurous acid band to the above mentioned small vessel 3, in which there is provided a small valve, which is fitted with a float 20, and is adapted to close the inlet to the inner pipe 2.

The oil flung out passes back through two scraping pipes 21 and 22 to an oil vessel 23 disposed above the cylinders.

On the outer tubular shaft 5 there is provided in the tank 4 a valve 24 the spindle 25 of which is free to move in radial direction.

When the machine stands still, the valve spindle 25 will allow the pressure difference between the two tanks to be equalized, and this will also be the case, when the pressure in the tank 4 becomes so high that it may overcome the centrifugal force acting on the spindle 25, the valve 24 being then opened so as to relieve the tank 4 from the excessive pressure.

Owing to the feature that the valve 24 is open, when the machine is to be started, the start will be facilitated, the fact that the valve 24 is open having for its consequence that no excess pressure will exist in the tank 4.

Having now particularly described and ascertained the nature of my said invention and in what manner the same is to be performed, I declare that what I claim is:

1. A refrigerating machine including a rotatable hollow shaft, an evaporator carried on one end thereof, a globular gas tank on the other end of the shaft, a gas compressor loosely mounted on the shaft within the tank, means for normally holding the compressor in horizontal position in the tank, an oil tank carried with the compressor and in communication therewith, a sulphurous acid receiving tank also carried with the compressor, a pair of separating rings secured in spaced relation on the inner surface

of the tank and in planes at right angles to the axis of the shaft for separating the condensed sulphurous acid from the oil, and scraping pipes mounted on the oil tank terminating adjacent the rings and within the tanks for respectively returning the separated oil and sulphurous acid to the oil tank and the sulphurous acid tank.

2. A refrigerating machine including a rotatable hollow shaft, an evaporator carried on one end thereof and in communication therewith, a gas tank carried on the other end of the shaft, a gas compressor loosely mounted on the shaft within the tank, means for normally holding the compressor in horizontal position in the tank, a valve including a casing mounted on the shaft and extending radially therefrom for equalizing the pressure in the evaporator and the tank and a valve member within the casing adapted to close due to centrifugal action upon the rotation of the shaft, and the valve member being also adapted to be opened when the gas in the tank rises beyond a predetermined pressure above that in the evaporator.

3. A refrigerating machine including a hollow rotatable shaft, an evaporator carried on one end thereof, a globular gas tank carried on the other end of the shaft, a gas compressor mounted on the shaft within the tank including a pair of cylinders loosely mounted on the shaft, a weight carried by the cylinders for holding the same in a horizontal diametrical plane of the tank, an oil tank carried with the cylinders and in communication therewith, a sulphurous acid receiving tank also carried with the cylinders, a pair of spaced perforated partition rings mounted within the tank in planes at right angles to the axis of the shaft for separating the condensed sulphurous acid from the oil, scraping pipes mounted on the oil tank terminating adjacent the rings and within the tanks, a valve controlled return pipe extending from the sulphurous acid tank through the hollow shaft to the evaporator, a valve including a casing mounted on the shaft and extending radially therefrom for equalizing the pressure in the evaporator and the tank, and a valve member within the casing adapted to close due to centrifugal action upon the rotation of the shaft and the valve member being also adapted to be opened when the gas in the tank rises beyond a predetermined pressure above that in the evaporator.

In testimony whereof I affix my signature in presence of two witnesses.
HOLGER NIELSEN.
